UNITED STATES PATENT OFFICE.

JAMES E. SHEAFFER, OF BURNHAM, PENNSYLVANIA.

HYDROCARBON-BURNER.

1,210,856.

Specification of Letters Patent. Patented Jan. 2, 1917.

Application filed October 28, 1915. Serial No. 58,421.

To all whom it may concern:

Be it known that I, JAMES E. SHEAFFER, a citizen of the United States, residing at Burnham, in the county of Mifflin and State 5 of Pennsylvania, have invented a new and useful Hydrocarbon-Burner, of which the following is a specification.

The present invention appertains to hydrocarbon or liquid fuel burners, and is particularly an improvement over the hydrocarbon burner disclosed in my Patent No. 10 1,140,621, issued May 25, 1915.

The object of the invention is the provision in a burner of the type disclosed in 15 said patent, of a novel refractory or metal discharge nozzle for enhancing the utility and efficiency of the burner, and novel means for atomizing and injecting the oil or other liquid fuel into the burner to provide the 20 combustible mixture which is forced under pressure through the discharge nozzle.

It is also within the scope of the invention to provide a hydrocarbon burner having the foregoing improvements, which is simple 25 and inexpensive in construction, and also practical and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made 30 within the scope of what is claimed without departing from the spirit of the invention.

The invention is illustrated in the accompanying drawing, wherein:—

Figure 1 is an elevation of the improved 40 burner, partly in section. Figs. 2 and 3 are cross sectional views taken on the lines 2—2 and 3—3 of Fig. 1.

In carrying out the invention, there is provided a frusto-conical or tapered casing 45 or body 1, having its largest end disposed forwardly, and having the inner integral nozzles 2 and 3 between its ends. The nozzles 2 and 3 project forwardly, the nozzle 2 being disposed in advance of the nozzle 3, 50 and the nozzle 3 being slightly smaller than the nozzle 2 and projecting into the basal or rear portion of the same. The forward end or tip of the nozzle 2 projects through the forward or largest end of the casing 1. 55 The rear or smallest end of the casing 1 is provided with a reduced portion or boss 4,

forming a rearwardly facing shoulder 5, and the casing 1 is also provided with three annular series of slots or air inlets 6, 7 and 8. The slots 6 are disposed between the basal portion of the nozzle 2 and the forward end of the casing, and the slots 7 are disposed between the basal portions of the nozzles 2 and 3, while the slots 8 are disposed between the basal portion of the nozzle 3 and the rear end of the casing 1. The forward end of the casing 1 is provided with an outturned annular flange 9 having the annular lip or rim 10.

A refractory discharge nozzle 11 has its 70 basal end seated against the forward end of the casing 1, and provided with an outstanding annular flange 12 fitting within the lip or rim 10 of the flange 9, and a ring or annulus 13 of angular cross section is fitted 75 over the basal portion and flange 12 of the nozzle 11 to coöperate with the flange 9 and its lip or rim 10 for clamping the basal flange 12 of the nozzle 11 in place. Bolts or other securing elements 14 are engaged 80 through the ring or annulus 13 and the flange 9, for clamping the parts together and whereby when the bolts 14 are loosened and removed, the parts may be separated. The free end of the nozzle 11 is flared or enlarged, as at 11^a, and the tapered portion of the nozzle has a relatively thick wall, while the wall of the nozzle decreases in thickness 85 from its basal to its free end. The nozzle 11 is provided with an annular series of 90 relatively large air inlet apertures or openings 11' adjacent its basal end, and with a second annular series of apertures or openings 11'' immediately in advance of and disposed between the apertures 11'. The 95 apertures 11'—11'' provide air inlets, whereby air can flow into the discharge nozzle for providing a more perfect combustible mixture, and the flaring of the nozzle 11 produces a larger flame, and allows the flame 100 to extend adjacent if not into the flared or bell mouth of the nozzle 11.

A frusto-conical or tapered shell or sleeve 15 is mounted for rotation upon the casing or body 1, and is preferably provided with 105 an outstanding handle or finger piece 15^a for enabling the shell 15 to be readily swung to open and closed positions. The oscillatory movement of the shell 15 is preferably limited by means of an arcuate slot 16 provided in the shell 15, and a stud or lug 16^a secured to the casing 1 and extending 110

through the slot 16. The shell 15 provides an air regulator, it being provided with three annular series of slots or openings 17, 18 and 19 coöperating with the respective slots 6, 7 and 8 of the casing 1 to be brought into and out of registration therewith, as the shell or regulator 15 is swung back and forth.

The casing is of circular cross section and has a smooth periphery whereby the shell is rotatable snugly upon the casing for opening and closing the air inlets of the casing.

The forward or largest end of the shell or regulator 15 abuts against the flange 9 of the casing 1, and a retaining nut 20 is threaded upon the reduced end 4 of the casing 1 and bears against the rear or smallest end of the shell 15 for mounting the same rotatably in place upon the casing. When the nut 20 and stop or lug 16^a are removed, the shell or regulator 15 may be removed off of the casing 1.

A tapered steam or air nozzle 22 has its smaller end 23 projecting into the smaller end of the casing 1 and into the larger end of the nozzle 3, the nozzle 22 being provided adjacent its smaller end with an enlarged portion 24 threaded within the smaller end of the casing 1. The larger end of the nozzle 22 which projects from the casing 1 is provided with a restricted opening or aperture 25, and the nozzle 22 is provided with a lateral nipple or inlet 26 for the attachment of a steam or pressure fluid pipe to supply steam, air or other pressure fluid into the nozzle 22.

A tapered oil or liquid fuel nozzle 27 projects into the nozzle 22 from the larger end thereof past the pressure fluid inlet 26, the nozzle 27 being provided at its larger end with a threaded portion 28 threaded within the opening 25, and with an enlarged threaded portion or head 29 bearing against the larger end of the nozzle 22 and adapted for the attachment of an oil or liquid fuel pipe to convey the oil into the nozzle 27. The nozzles 22 and 27 are coaxial with the other nozzles and casing.

The nozzles 27, 22, 3, 2 and 11 are arranged in a longitudinal series, with the tips of the nozzles 27, 22, 3 and 2 projecting into the basal portions of the respective nozzles immediately in advance thereof. The nozzles 27, 22, 3, 2 and 11 are also increased in size in succession. The parts of the burner may be readily cast from metal or otherwise manufactured, and may be readily assembled with one another, as well as being readily separated for purpose of cleaning, repair or replacement.

In use, the steam or pressure fluid is supplied to the nozzle 22 by way of the inlet or port 26, and the oil or other liquid fuel is supplied into the nozzle 27. When the steam or pressure fluid enters the nozzle 22

it passes around the nozzle 27 to heat the oil therein, whereby the oil is more readily atomized, and the steam in flowing past the tip of the nozzle 27 will atomize the oil and admix the same with the steam. The mixture is directed or forced through the nozzles 3, 2 and 11 in succession, and the passage of the mixture through each of said nozzles will draw in air through the respective slots in the casing and shell. The mixture in being discharged from the nozzle 22 into the nozzle 3 will create a suction between the nozzle 3 and tip 23 of the nozzle 22, so that air will be drawn through the registering slots 8-19. Similarly, when the mixture is discharged from the nozzle 3 to the nozzle 2, air will be drawn through the registering slots 7-18, and in a like manner, when the mixture passes from the nozzle 2 through the nozzle 11, air will be drawn through the slots 6-17. Air is also drawn through the apertures 11'-11''. The mixture burns adjacent the discharge nozzle 11, said nozzle being of refractory material in order to prevent the destruction thereof by the heat. The present burner provides a non-oxidizing flame and produces a perfect mixture and combustion at the tip of the burner, no additional air being required to support combustion. The flame produces a minimum amount of smoke, and the burner uses a minimum amount of fuel for a maximum amount of heat. The nozzle 11 provides for a greater volume of the flame, and the burner can be used either as a high or a low pressure burner. The burner can be used upon various furnaces, boilers, and the like.

Due to the construction of the present burner, streams of air will be admitted through the slots of the casing and shell or regulator and will pass through the annular spaces between the concentric nozzles, to admix with the steam and atomized fuel, to thoroughly agitate and mix the steam, air and fuel for providing a highly combustible mixture. The amount of air admitted into the casing may be regulated by swinging or adjusting the shell or regulator 15 to bring the slots thereof more or less out of registration with the slots of the casing 1.

What is claimed as new is:

1. A hydrocarbon burner embodying a casing having an open end and a nozzle projecting through said open end, a refractory discharge nozzle having a relatively thick cylindrical end portion abutting said end of the casing and in registration therewith, said end of the nozzle having an outwardly relatively thick flange, and means clamping said flange against the end of the casing, the free end of the discharge nozzle being flared, said nozzle decreasing in thickness to the flared end, the first mentioned nozzle projecting within the first mentioned

end of the refractory nozzle, and the refractory nozzle having an annular series of air inlet openings in its periphery disposed in a plane spaced slightly from the end of the 5 first mentioned nozzle.

2. A hydrocarbon burner embodying a casing having a nozzle therein and air inlets adjacent the basal end of said nozzle, a pressure fluid nozzle tapered from one end 10 to the other and having an enlarged portion adjacent its smaller end threaded through one end of the casing and having its smaller end projecting into the basal portion of the first mentioned nozzle, said pressure fluid 15 nozzle having a lateral pressure fluid inlet port adjacent its larger end and a reduced

opening at its larger end, and a tapered liquid fuel nozzle threaded through the opening of the larger end of the pressure fluid nozzle and having an enlarged portion at 20 its larger end bearing against the larger end of the pressure fluid nozzle, the liquid fuel nozzle being tapered similar to the pressure fluid nozzle and extending past the pressure fluid inlet port. 25

In testimony that I claim the foregoing as my own, I have hereto affixed my signature in the presence of two witnesses.

JAMES E. SHEAFFER.
